(57) **CLAIM**

The ornamental design for a pressure cooker, as shown and described.

DESCRIPTION

The patent or application file contains at least one drawing executed in color. Copies of this patent or patent application publication with color drawing(s) will be provided by the Office upon request and payment of the necessary fee.

1. Pressure cooker

1.1: Front

1.2: Back

1.3: Left

1.4: Right

1.5: Top

1.6: Bottom

1.7: Perspective

The claimed pressure cooker is a cylinder; The front face of cylinder is provided with a rounded rectangular panel; The middle and lower part of the panel is provided with a cylindrical knob; The top of cylinder is provided with a convex handrail penetrating the its diameter, and handrail has a wide upper edge.

(Continued)

The portion of the design shown in the color red is for the purpose of illustrating the portion of the pressure cooker and forms no part of the claimed design.
